Primary Examiner — Wan Laymon(74) *Attorney, Agent, or Firm* — Green Mountain Innovations LLC; Alan Cote(57) **CLAIM**

The ornamental design for an oral appliance, as shown and described.

DESCRIPTION

FIG. 1 is a top, front, right side perspective view of an oral appliance;

FIG. 2 is a front elevation view thereof;

FIG. 3 is a rear elevation view thereof;

FIG. 4 is a right side elevational view, the left side being a mirror image thereof;

FIG. 5 is a top plan view thereof; and,

FIG. 6 is a bottom plan view thereof.

The broken lines in the drawings are included for the purpose of illustrating portions of the oral appliance and form no part of the claimed design.
